UNITED STATES PATENT OFFICE.

WILLIAM J. CAMPBELL, OF DAYTON, VIRGINIA.

HAME-TUG.

No. 836,920.

Specification of Letters Patent.

Patented Nov. 27, 1906.

Application filed February 14, 1906. Serial No. 300,963.

To all whom it may concern:

Be it known that I, WILLIAM J. CAMPBELL, a citizen of the United States, residing at Dayton, in the county of Rockingham and State of Virginia, have invented a certain new and useful Improvement in Hame-Tugs, of which the following is a full, clear, and exact description.

This invention relates to hame-tugs, and generally to that class of hame-tugs represented in my Patent No. 595,145, dated December 7, 1897, in which the clip-iron is arranged between leather layers and in connection with a box-loop and a buckle.

The present invention has for its object to economize in the cost of manufacture of hame-tugs of this general character and to insure the stability of the box-loop.

In the accompanying drawings, illustrating my invention, in the several figures of which like parts are similarly designated, Figure 1 is a top plan view with the top of the box-loop in horizontal section to show the stitching. Fig. 2 is a longitudinal section. Fig. 3 is a transverse section taken in the plane of line A B, Fig. 2. Fig. 4 is a transverse section taken in the plane of line C D, Fig. 2. Fig. 5 is a perspective view of the built-up leather portion of the tug before the box-loop is applied for stitching. Fig. 6 is a perspective view of the box-loop detached, and Fig. 7 is a perspective view of the clip-iron.

The foundation-piece 1 is constructed of a single piece of leather of suitable shape and length, and the box or trace loop 2 is arranged directly upon the foundation-piece, as will be described. The clip end of the tug is built up by a filling-piece 3, placed directly upon the foundation-piece 1 and extending to and abutting against and of substantially the same thickness as the bottom of the box or trace loop 2, thus forming a continuous and uninterrupted surface from the clip end to the buckle end of the box or trace loop. Above the filling-piece 3 is arranged another filling or dividing piece 4, which extends only to the clip end of the box or trace loop 2. A piece of leather 5 is adapted to fit within the box or trace loop 2 over the bottom thereof and with one end abutting against the edge of the piece 4 and its other end extending to within a short distance of the buckle end of the box or trace loop, and a separate or independent chape or buckle-loop 6 is secured to the end of the piece 5, as by means of a staple 7 (see Figs. 1, 2, and 5) or stitches or any

other suitable fastening, and these parts 5 and 6 contribute to form a tongue, as clearly shown in Fig. 5, which corresponds functionally to the tongue in my patent before mentioned, but differs from it in being made up of scraps of leather instead of the more expensive single piece of the patent.

In the present construction the pieced tongue is attached to a separate and independent facing-piece 8 instead of being in one piece with it, as in the patent, and this facing-piece 8 is arranged above the dividing piece 4 and has a narrowed portion 9, adapted to extend within the box or trace loop 2 over the abutting edges of the pieces 4 and 5 and to which the piece 5 may be secured, as by rivets 10 or stitches or any other suitable fastenings. The facing 8 may be ornamented in any suitable manner, as by means 75 of a covering 11 of patent leather.

In carrying out my invention it is preferable to put the parts 1, 3, 4, 5, 6, and 8 together as shown in Fig. 5 and unite the parts 1, 3, 4, and 8 by a line of stitching 12 along their edges, as shown in Figs. 1, 3, and 5. The box or trace loop 2 is then slipped upon the pieced tongue 5 and 6, with its bottom wall between the tongue and foundation-piece 1 and its inner edge abutted 85 against the edge of the piece 3, and then the piece 5, box or trace loop 2, and the foundation 1 are stitched together by lines of stitching 13 adjacent to the inner walls of the box or trace loop 2, as shown in Figs. 1 and 4. 90 The leather portion of the tug as thus constructed is adapted to be used in connection with a clip-iron having the usual eye 14, a short arm 15, and a long arm 16, and the long arm 16 of said clip-iron is adapted to be 95 slipped into a pocket 17 formed by and between the filling-piece 3 and the bottom of the box-loop 2 upon one side and the filling-piece 4 and the piece 5 upon the other side, and said long arm projects beyond the box- 100 loop and is provided with a suitable perforation 18 to receive the buckle-loop fastening. The short arm 15 of the clip-iron is received into a pocket 19, formed by the filling-piece 4 upon one side and the facing 8 upon the other 105 side, and said short arm is thus concealed and effectually sustained against spreading under strain. The chape or buckle-loop 6 is provided with the usual tongue-opening 20 and the openings or perforations 21 for the 110 fastening-rivet 22.

In applying the buckle it is placed within

the chape or buckle-loop in the usual manner and the loop bent downward and inward under the projecting end of the long arm of the clip-iron, with its perforations in alinement 5 with perforations in the clip-iron and also in the projecting end of the foundation 1 and the rivet 22 or any other suitable fastening passed therethrough and secured in place.

In the present invention the foundation 1 10 is made of a single piece or thickness of leather, and the other parts, and particularly the facing 8 and the piece 5 and chape or buckle-loop 6, are constructed of short lengths or scraps of leather instead of using a single piece for constructing the facing and tongue and chape or buckle-loop as in some prior constructions, and by this construction the cost of producing the tug is greatly reduced by reason of the difference in cost of 15 the different grades of leather used.

In the present invention the leather portion of the tug is constructed with the clip-iron pockets and the open chape or buckle-loop and the stitched-in box or trace loop as 20 a finished article, and hence said leather portion may be supplied with a clip-iron and buckle of any style or finish desired by the purchaser, the clip-iron being readily inserted in the pockets and the buckle placed 25 in the loop or chape and the parts securely locked together by simply putting the rivet in place at the buckle end of the tug.

The construction herein shown and described is susceptible of various changes 30 without departing from the principle or scope of the invention.

What I claim is—

1. A hame-tug, having a leather foundation-piece, a box-loop arranged upon said 40 foundation-piece, the hame end of the device having clip-iron pockets, built up on the foundation-piece by means of a filling-piece, a dividing-piece and a facing-piece substantially coterminous with each other and extending to and terminating at the box-loop, and a pieced tongue extending from the built-up hame end through the box-loop, the pieced tongue, box-loop and foundation-piece being stitched together.

50 2. A hame-tug, having a leather foundation-piece, a box-loop, a leather filling-piece extending from one end of the foundation-piece to the box-loop and of substantially the thickness of the material of the box-loop 55 next to the foundation-piece, a leather dividing-piece arranged above and coterminous with the first-mentioned filling-piece, and a facing-piece arranged above the dividing-piece, there being clip-iron pockets on the 60 opposite sides of and separated by the dividing-piece, the box-loop arranged on the foundation-piece and a pieced tongue attached to the facing-piece and extending through the box-loop, the pieced tongue and the bottom 65 of the box-loop being stitched to the founda-

tion-piece for substantially the length of the box-loop, and a chape or buckle-loop forming the outer end of the pieced tongue and said pieced tongue forming a continuation of the lower clip-iron pocket.

3. A hame-tug, comprising a leather portion constructed of a foundation-piece, a box-loop arranged upon said foundation-piece, a facing, a sectional or pieced tongue extending from said facing through the box-loop 70 and terminating in a chape or buckle-loop, and a filling-piece interposed between the foundation-piece and facing and extending only to the box-loop, the said parts being stitched along their edges and within the 80 walls of the box-loop to the buckle end thereof and constituting a long and short pocket, combined with a clip-iron having a long and a short arm, the short arm entering the pocket between the facing and filling piece, 85 and the long arm entering the pocket between the foundation and filling piece and extending through the box-loop between the sectional or pieced tongue and the bottom 90 of the box-loop, and a metal fastening passed through the chape or buckle-loop, the end of the long arm of the clip-iron and the foundation, to secure the buckle and clip-iron to the leather portion.

4. A hame-tug, comprising a leather portion constructed of a single foundation-piece, a box-loop arranged upon said foundation-piece, a facing, and a sectional or pieced tongue extending from said facing through said box-loop and terminating in a chape or 95 buckle-loop beyond said box-loop, a filling or dividing piece between said foundation and facing extending to the box-loop only, a filling-piece arranged between the dividing-piece and the foundation and extending to 100 the edge of the bottom of the box-loop, the said parts being stitched together along their edges and within the side walls of the box-loop and forming a short pocket between the facing and dividing piece extending to the box-loop and a long pocket between the foundation, its superposed filling and box-loop bottom and the dividing-piece and sectional or pieced tongue, combined with a long and short arm 105 clip-iron having its short arm entering the short pocket and its long arm entering the long pocket and extending beyond said box-loop, and a metallic fastening passed through the buckle-loop, clip-iron and foundation for 110 securing the clip-iron and buckle to the leather portion.

In testimony whereof I have hereunto set my hand this 12th day of February, A. D. 1906.

WILLIAM J. CAMPBELL.
